UNITED STATES PATENT OFFICE

157,716

FISHING POLE HOLDER

Carl D. Wortman, Coshocton, Ohio

Application May 13, 1949, Serial No. 2,621

Term of patent 14 years

(Cl. D31—4)

To all whom it may concern:

Be it known that I, Carl D. Wortman, a citizen of the United States, residing at Coshocton, in the county of Coshocton and State of Ohio, have invented a new, original, and ornamental Design for a Fishing Pole Holder, of which the following is a specification, reference being had to the accompanying drawings, forming a part thereof.

I claim:

The ornamental design for a fishing pole holder, as shown.

CARL D. WORTMAN.
